SUCTION CLEANER

Filed Feb. 16, 1929

Inventor
Wilmor H. Tucker

BY Harry S. Denmarz
Attorney

UNITED STATES PATENT OFFICE

WILMER H. TUCKER, OF CANTON, OHIO, ASSIGNOR TO THE HOOVER COMPANY, A CORPORATION OF OHIO

SUCTION CLEANER

Application filed February 16, 1929. Serial No. 340,544.

In the modern suction cleaner, maximum cleaning efficiency has been attained through the mediums of high suction and positive agitation. It is a common experience, however, in the design of single nozzle machines encompassing both high vacuum and positive agitation that the including of the positive agitator within the nozzle mouth necessitates the building of the nozzle in a 10 relatively large size with a correspondingly wide mouth. The action of the vacuum in the nozzle, when the machine is in operation, is to draw the carpet up within the mouth against the agitator. In the operation of a suction cleaning machine the section of floor covering drawn into the nozzle mouth increases with the width of said mouth and the force necessary to break the seal of the nozzle lips and the covering varies with the displacement. With the 20 vacuum of the cleaner increased to the point of maximum air-cleaning efficiency, in the usual machine having a wide nozzle mouth, the displacement of surface covering at the 25 nozzle mouth is so excessive as to greatly increase this breaking force and so raise the propelling force necessary for the cleaner to a prohibitive point. In view of this condition it has been necessary heretofore to 30 compromise, because of the necessarily large nozzle mouth, by the lowering of the vacuum below the point of maximum cleaning efficiency to a point where the propelling force has not been so high as to be burdensome 35 to the user.

In a suction cleaner constructed in accordance with this invention, use may be made of both the maximum cleaning power of the high suction and of positive agitation without need for compromise with the resulting efficiency sacrifice. A structure has been provided in which there is no conflict between the two means and also in which higher vacuums than any heretofore 45 feasible in the portable suction cleaner are found.

The primary object of this invention is, therefore, to provide a new and novel suction cleaner construction having greater 50 cleaning efficiency than any known hereto-

fore. A second object of this invention is to provide a suction cleaner in which no sacrifice of the air-cleaning power has been made through the incorporation in the machine of positive agitating means. A 55 further object of this invention is to provide a suction cleaner having both high and low suction nozzles, the vacuum for the high suction nozzle being supplied by two fans in tandem and the vacuum for the low 60 suction nozzle being supplied by one fan. A still further object of this invention is to provide in a suction cleaner construction a high pressure and a low pressure nozzle, the low pressure nozzle encompassing agitating 65 means.

Reference is now made to the drawing which shows a cross section through a suction cleaner constructed in accordance with this invention. The body of the machine 70 comprises a motor casing 1; a fan chamber 2 connected directly to the motor casing 1; a central chamber 3 opening into the fan chamber 2 and directly connected to the low suction nozzle 4; a second fan 75 chamber 5 positioned directly forward of the intermediate or central chamber 3 and interiorly connected thereto by exhaust outlet 6; and a high-vacuum nozzle 7 connected directly to the fan chamber 5. The machine 80 is supported upon the surface undergoing cleaning with the nozzle mouths in the proper working relation by front supporting wheels 8, of which one is shown, and by a rear supporting wheel 9 attached to the 85 motor casing. A handle bail 10 is pivotally connected at 11 to the motor casing in order that the machine may be propelled.

The operative mechanism comprises a motor, not shown, positioned in the casing 1; 90 from which motor shaft 12 extends into the fan chamber 2 and on into the intermediate chamber 3. Positioned fixedly upon the shaft 12 in the fan chamber 2 is the fan 13 adapted, in the operation of the machine, to 95 draw air from the intermediate chamber 3 and exhaust same through the exhaust outlet 14 of the fan chamber 2. The outlet 14 is adapted to receive the opening of a dust bag or suitable depository for matter drawn 100

through the machine and exhausted therefrom.

Opening directly into the intermediate chamber 3 and positioned therebelow is the 5 low-vacuum nozzle 4 within which is rotatably mounted the motor driven agitator 15 of a common and well known type. Driving means for agitator 15 consists of a belt 16 directly connected to the pulley 17 on the 10 shaft 18 which is directly connected, through a mechanism hereinafter described, to the motor shaft 12.

Positioned within the fan chamber 5 and 15 fixedly mounted upon the shaft 18, which is carried by bearing 19 in the rear wall of said fan chamber, is the fan 20 functioning, in the operation of the machine, to draw air from the high-vacuum nozzle 7, carried 20 by the forward wall of chamber 5, and exhaust same through the exhaust outlet 6 into the central chamber 3. The exhaust outlet 6 is directly connected to the central chamber 3 and is held by securing means 21, 21, etc.

25 The shaft 18 upon which the forward fan 20 and the driving pulley 17 are mounted is directly connected to the motor shaft 12, in the operation of the machine, by means of a slideable collar 22 which overlies the ends 30 of the two shafts and which is provided with grooves 23 and 24. Upon the shafts 12 and 18 are outstanding pins 25 and 26, respectively, and positioned between the rear end of the collar 22 and the hub of the fan 13 35 is a spring 27 which serves at all times to urge the collar 22 in the direction of the shaft 18. The driving relation between the two shafts is secured by permitting the spring 27 to force the collar 22 forward until 40 it encloses the end of shaft 18 with the pin 25 seated within the groove 23. Relative movement between the two shafts is then prevented through the end of both shafts being held in fixed relation in the 45 collar 22 through the respective pin and groove relationships. Positioned in the central chamber 3 directly above the collar 22 is the removable cap 28 through which access 50 may be had to the interior of chamber 3 when it is desired to disconnect the two shafts.

In the operation of a cleaner constructed 55 in accordance with this invention the forward nozzle 7 is provided with suction by the action of fans 20 and 13, the construction being such that an air passage is provided from said nozzle through the fan chamber 5 into chamber 3, which is the low-pressure area of the fan 13, and thence 60 by the action of fan 13 into exhaust outlet 14. This series or tandem arrangement of the fans provides the nozzle 7 with a very high vacuum because it makes use of the draft of both fans, the fan 13 functioning to 65 reduce the back pressure on fan 20, thereby

increasing the effective suction in the nozzle 7 by the same amount as the decrease in the back pressure on fan 13. The nozzle 7, as it contains no agitator, is made of a relatively small width thereby permitting 70 of the use of high vacuum without undue displacement of the surface covering which would increase the resistance to movement of the machine.

The nozzle 4 is provided with suction 75 which is low as compared to that provided for nozzle 7 for while the relatively large capacity fan 13 displaces the air within the chamber 3, and so the nozzle 4, the actual reduction in pressure is relatively low because of the fact that the fan 20 exhausts 80 therein tending to build up the pressure. The suction provided for nozzle 4 is therefore the suction which the fan 13 can provide for it after it has reduced the pressure 85 built up by the fan 20 exhausting into chamber 3. With fan 13 of only moderately greater capacity than the fan 20 the effective suction of nozzle 4 will be comparatively 90 low. This condition is desirable in the nozzle 4, however, because of the necessarily 95 relatively great width required by the presence of the agitator therein, for with a high vacuum in this nozzle the floor covering would be drawn too far therein and the 100 resistance to movement of the cleaner excessively increased.

In the operation of the machine the surface covering is acted upon by the high suction of the straight-air nozzle 7 and by the 100 low suction and agitation provided by the nozzle 4. As the suction cleaner is propelled over the surface covering the foreign matter 105 therein is loosened or dislodged by the action of the agitator and partly removed by the 110 inrush air in the low-pressure nozzle. Upon the high-vacuum nozzle passing over the same area the dirt is completely removed by the force of the inrush air. It is to be understood that both functions are necessary for maximum cleaning efficiency.

In the event that it is necessary to equip 115 the machine with a new belt for driving the agitator 15, the old belt may be removed and taken out of the chamber 3 through the disconnection of the shafts 12 and 18 by sliding of the collar 22 rearwardly upon the shaft 12 thereby compressing the spring 27 and exposing the spaced ends of the two 120 shafts. The old belt can then be displaced downwardly therebetween and then encloses only the rotor 15. The removal of the belt from rotor 15 is accomplished by removing one end wall of the nozzle and displacing the rotor through the resulting aperture. Nozzles of the removable end type are old and well known and the manner in which the rotor is removed forms no part of the 125 present invention. The connecting of the 130

new belt would be simply the reverse operation.

Means have also been provided for use of the invention with dusting tools through the provision of an opening 29 in the forward face of the nozzle 7. In the ordinary operation of the machine as a suction cleaner the opening 29 is closed by means of a cap 30, said cap being easily removable so that the insertion of the machine-end of the dusting tool is an easy matter. With the dusting tool inserted through the opening 29 the nozzle 7 will be entirely cut off providing a direct opening into the fan chamber 5 for the tool. In order that the effective suction of the two fans in tandem may not be reduced by air being drawn through the rear nozzle 4 when the dusting tools are being used, a closure plate 31 is provided which is adapted to be swung into position over the mouth of said nozzle entirely closing same. The closure plate 31 is pivoted at 32 to the rear wall of the nozzle 4 and, in the ordinary operation of the cleaner, is held up out of the way under the fan chamber by the action of spring 33.

From a consideration of the foregoing description and the drawing relating thereto, it is apparent that applicant has provided a new and novel construction for suction cleaners incorporating the desirable features of both high-vacuum straight-air machines and relative low-vacuum machines supplied with positive agitation means and which is unaccompanied by the attendant difficulties which have heretofore been present in such combinations.

I claim:

1. A suction cleaner having a plurality of nozzles, an agitator in one of said nozzles, a plurality of fan chambers one connected to each nozzle, means connecting said fan chambers in series and fans within said fan chambers.

2. In a suction cleaner, a plurality of nozzles, suction-producing means connected to each of said nozzles, means to conduct the exhaust of one of said suction-producing means to the intake of a second suction-producing means, and agitating means in the nozzle connected to said second suction-producing means.

3. A suction cleaner having a narrow nozzle and a wide nozzle, an agitator within said wide nozzle, a plurality of fans operatively connected in tandem to said narrow nozzle and one of said fans connected to said wide nozzle.

4. In a suction cleaner, a nozzle, a second nozzle, a plurality of suction-producing means connected in tandem to said first nozzle, one of said suction-producing means only being connected to said second nozzle, for the purpose of producing a higher suc-

tion in said first nozzle and a lower suction in said second nozzle.

5. A suction cleaner comprising a motor casing, a fan chamber adjacent said motor casing, a nozzle adjacent said fan chamber opening into said fan chamber, a second fan chamber adjacent said nozzle, an outlet member providing a passage from said second fan chamber to said first fan chamber and a second nozzle adjacent said second fan chamber exhausting therein.

6. A suction cleaner comprising a motor casing, a fan chamber adjacent said motor casing, a nozzle adjacent said fan chamber and open thereto, a rotary agitator positioned therein, a second fan chamber adjacent said nozzle, a conduit providing a passage from said second fan chamber to the eye of the first fan chamber, a second nozzle adjacent said second fan chamber and open thereto, a driven shaft extending from said motor casing through said fan chambers, fans positioned thereon in said chambers and power transmission means connecting said shaft to said agitator.

7. A suction cleaner including a plurality of suction nozzles, a plurality of means for setting up a high vacuum in one of said nozzles and means for setting up a low vacuum in a second nozzle, characterized by the fact that said second-mentioned means is a part of said first-mentioned means.

8. In a suction cleaner, a plurality of nozzles, an agitator in one of said nozzles, a plurality of means for setting up a high suction connected to one of said nozzles, means for setting up a low suction connected to said agitator-containing nozzle, characterized by the fact that said second-mentioned means is a part of said first-mentioned means.

9. In a suction cleaner, a plurality of nozzles, a fan chamber connected to each of said nozzles, a fan in each of said fan chambers, a single source of power connected to said fans, a conduit leading from the exhaust outlet of one fan chamber to the inlet of a second fan chamber, agitating means positioned in the nozzle connected to said second fan chamber, and means operatively connecting said agitating means to said source of power.

10. In a suction cleaner, a plurality of parallel nozzles, a fan chamber connected to each of said nozzles, a fan in each of said fan chambers, a motor-driven shaft extending through said fan chambers connecting to said fans, a conduit leading from the exhaust outlet of one fan chamber to the inlet of a second fan chamber, a rotary agitator in the nozzle connected to the second fan chamber, and a power-transmitting belt connecting said agitator to said shaft.

11. In a suction cleaner, a plurality of nozzles, a plurality of suction-producing

means connected to one of said nozzles, a part only of said suction-producing means being connected to a second nozzle, means to prevent the entrance of air into said second nozzle, and means to receive a dusting tool in said first nozzle.

12. In a suction cleaner, a nozzle, a second nozzle, a suction-producing unit interiorly connected directly to said first-mentioned nozzle, a suction-producing means interiorly connected directly to said second-mentioned nozzle, means connecting said suction-producing means in tandem, said first-mentioned nozzle having a removable portion adapted to receive a connecting inlet tube, and means to prevent the entrance of air into said second-mentioned nozzle.

13. In a suction cleaner, a nozzle, a second nozzle, a fan chamber having an inlet and an exhaust opening connected to said first-mentioned nozzle, a fan chamber connected to said second-mentioned nozzle, fans in said fan chambers, a conduit connecting the exhaust opening of said first-mentioned fan chamber to the second fan chamber, said first-mentioned nozzle having an opening in alignment with the inlet of the connecting fan chamber, said opening being adapted to receive a connecting tube of a dusting tool.

30 Signed at North Canton, in the county of Stark, and State of Ohio, this 7th day of February, A. D. 1929.

WILMER H. TUCKER.
